FASTENER

William L. Sparks, Hartsdale, N. Y.

Application December 9, 1943, Serial No. 513,557

9 Claims. (Cl. 24—153)

This invention relates to fasteners adapted for use in securing letters and other papers for filing and particularly to fasteners having two spaced tongues which pass through the papers to be secured and through similarly spaced perforations in a retainer or keeper over which the tongues are bent.

It is the object of the present invention to provide a simple and effective fastener embodying a keeper with a locking device which will securely hold the tongues of the fastener and permit release thereof when the file is to be opened.

Other objects and advantages of the invention will be apparent as it is better understood by reference to the following specification and the accompanying drawing, in which:

Fig. 1 is a sectional view of a file illustrating the application of the improved fastener thereto;

Fig. 2 is a perspective view illustrating the keeper with the locking means separated therefrom;

Fig. 3 is a plan view of the keeper showing the locking means partially withdrawn;

Fig. 4 is a section on an enlarged scale on the line 4—4 of Fig. 3;

Fig. 5 is a section on an enlarged scale on the line 5—5 of Fig. 3; and

Fig. 6 is a section on an enlarged scale on the line 6—6 of Fig. 3.

Referring to the drawing, 5 indicates the base of the fastener having spaced tongues 6 adapted to be bent as indicated and to pass through the file of papers 7. The ends of the tongues project through perforations 8 near the ends of the keeper 9 which rests upon the uppermost paper of the file.

The keeper 9 consists of a strip of metal having two longitudinal ribs 10 formed on the face or upper surface thereof by pressing or otherwise forcing up the body of the strip. The ribs stiffen the keeper to prevent bending thereof.

Near the right hand end of the keeper, as viewed in the drawing, between the perforation 8 and that end of the keeper, the metal is cut and forced upwardly from the plane of the keeper to provide a saddle 11.

The locking device comprises an elongated member 13 having a rib 14 formed longitudinally thereof by pressing or otherwise forcing up the body of the metal to afford stiffness. At one end, the member 13 is provided with a clip 15, the edges 16 of which are bent downwardly and inwardly to embrace the edges of the keeper 9. The opposite end of the member 13 is preferably

provided with a rounded end 17 which is adapted to pass under the saddle 11. Preferably the saddle 11 is struck up slightly at its central portion 12 to accommodate the rib 14, thus affording a guide to maintain the member 13 in proper assembled relation with the keeper 9.

The clip 15 may be provided with depressions 18 formed by punching the metal slightly to cooperate with similar depressions 19 at the end of the keeper 9. Similarly the end 17 may be formed with a depression 20 to cooperate with a similar depression 21 on the keeper 9. These depressions by engagement with each other tend to hold the member 13 in locking position but permit movement thereof under slight pressure. If desired the friction between the clip 15 and the keeper may be utilized to hold the member 13 in locking position.

In using the device, the member 13 is withdrawn to the right, viewing Fig. 3, until the clip 15 engages the saddle 11. The tongues 6 may then be threaded through the perforations 8 and bent over the face of the keeper as indicated in Fig. 3. When the tongues 6 have been bent, the member 13 is moved to the left viewing Fig. 3 until the depressions 18 engage the depressions 19, thus locking the fastener with the tongues 6 securely held against release. To release the fastener it is merely necessary to slide the member 13 to the right until the tongues 6 are again free. The keeper may then be removed. When it is replaced it is again locked in the same manner. The member 13 can be moved in either direction by slight pressure of the thumb or finger.

Various changes may be made in the details of the apparatus without departing from the invention or sacrificing the advantages thereof.

I claim:

1. A keeper for file fasteners having perforations adjacent its opposite ends, an elongated member having means at one end extending around the side edges of the keeper and forming a sliding connection therewith, and means formed from the body of the keeper between one of the perforations and the adjacent end of the keeper in guiding engagement with the elongated member, said last-mentioned means restraining the elongated member against lateral movement while permitting said member to move longitudinally of the keeper.

2. A keeper for file fasteners having perforations adjacent its opposite ends, an elongated member having means at one end extending around the side edges of the keeper and forming

a sliding connection therewith, and a saddle struck from the body of the keeper adjacent one end and slidably engaging the edges of the elongated member to restrain it against lateral movement while permitting it to move longitudinally of the keeper.

3. A keeper for file fasteners having perforations adjacent its opposite ends, an elongated member having a longitudinally-extending stiffening rib and means at one end extending around the side edges of the keeper and forming a sliding connection therewith, and a saddle struck from the body of the keeper adjacent one end, said saddle having a portion conforming to the shape of the longitudinally-extending stiffening rib of the elongated member and engaging it and restraining the elongated member against lateral movement while permitting it to move longitudinally of the keeper.

4. A keeper for file fasteners having perforations adjacent its opposite ends, an elongated member having means at one end at least in part embracing the side edges of the keeper and forming a sliding connection therewith, and a saddle struck from the body of the keeper between one of the perforations and the adjacent end of the keeper, the elongated member extending beneath said saddle, and the saddle having a portion to engage the longitudinally-extending member and to restrain it against lateral movement while permitting it to move longitudinally of the keeper.

5. A keeper for file fasteners having perforations adjacent its opposite ends, an elongated member having means at one end at least in part embracing the side edges of the keeper and forming a sliding connection therewith, the keeper having a saddle formed from the body thereof between one of the perforations and the adjacent end of the keeper, the elongated member extending beneath said saddle and the saddle being adapted to be engaged by the edge-embracing means of the elongated member and thereby act as a stop to limit longitudinal movement of the elongated member relative to the keeper in one direction, said saddle also restraining the longitudinal member against lateral movement while permitting said member to move longitudinally of the keeper.

6. In binding means for papers or the like of the type comprising a base member having prongs projecting substantially normally therefrom and adapted to extend through sheets of paper and to be bent towards one another over the papers and a keeper for the bent-over prongs; the improvement which comprises a keeper having perforations adjacent its opposite ends and an elongated member having means at one end to at least in part embrace the edges of the keeper and form a sliding connection therewith, and re-

taining means between one of the perforations and adjacent one end of the keeper, the elongated member extending through said retaining means and being movable longitudinally of the keeper to locking and releasing positions.

5 7. In binding means for papers or the like of the type comprising a base member having prongs projecting substantially normally therefrom and adapted to extend through sheets of paper and to be bent towards one another over the papers and a keeper for the bent-over prongs; the improvement which comprises a keeper having perforations adjacent its opposite ends and an elongated member having means at one end extending around the side edges of the keeper and forming a sliding connection therewith, and retaining means formed from the body of the keeper between one of the perforations and the adjacent end of the keeper, the elongated member extending through said retaining means and being movable longitudinally of the keeper to locking and releasing positions.

10 8. In binding means for papers or the like of the type comprising a base member having prongs projecting substantially normally therefrom and adapted to extend through sheets of paper and to be bent towards one another over the papers and a keeper for the bent-over prongs; the improvement which comprises a keeper having perforations adjacent its opposite ends, an elongated member having a longitudinally-extending stiffening rib and means at one end extending around and embracing the side edges of the keeper and forming a sliding connection therewith, and retaining means on the keeper between one of the perforations and the adjacent end of the keeper in guiding engagement with the elongated member, the elongated member extending through said retaining means and being movable longitudinally of the keeper to locking and releasing positions.

15 9. In binding means for papers or the like of the type comprising a base member having prongs projecting substantially normally therefrom and adapted to extend through sheets of paper and to be bent towards one another over the papers and a keeper for the bent-over prongs; the improvement which comprises a keeper having perforations adjacent its opposite ends and longitudinally-extending stiffening ribs, and an elongated member slidably supported on and movable longitudinally of the keeper to locking and releasing positions, the elongated member normally lying between the longitudinally-extending ribs of the keeper and having a wider clip portion at one end extending around and embracing the side edges of the keeper and forming a sliding connection therewith.
